Charles N. Wilson

ATTORNEY.

Patented Oct. 6, 1925.

UNITED STATES PATENT OFFICE.

JOHN A. SPERRY, OF MUNNSVILLE, NEW YORK.

MOLDING FLASK.

Application filed April 19, 1922. Serial No. 555,574.

To all whom it may concern:

Be it known that I, JOHN A. SPERRY, residing at Munnsville, county of Madison, and State of New York, have invented certain new and useful Improvements in a Molding Flask, of which the following is a specification.

This invention relates to improvements in flasks for use in molding, and has reference specifically to a guide or centering pin, by means of which the two parts of a flask may be held in position relatively to one another.

One object of the invention is to provide a pin which may be detachably mounted to one part of a flask, and provided with a resilient portion, so designed as to engage against the walls of a suitable bore formed in the other part of the flask, the resilient portion insuring that the two parts of the flask will be properly centered and locked in position.

Another object of the invention is to provide a new and improved pin for the purpose described, which shall be cheaply and strongly made, which shall provide a relatively secure lock for the two parts of the flask, and which shall at the same time offer but little resistance to the separation of the two parts.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawing, wherein I have shown a preferred form of embodiment of my invention:

Figure 1 shows a vertical cross-sectional view through a two-part flask, showing the pins in operative position.

Figure 2 is a bottom plan view of the cope.

Figure 3 is a longitudinal cross-section of one form of pin.

Figure 4 is a view in elevation of the pin shown in Figure 3.

Figure 5 is a vertical cross-sectional view of a modified form of pin.

Figure 6 is a view showing a modified form of pin, parts being broken away.

Figure 7 is a top plan view of the device shown in Figure 6.

Figure 8 is a view in side elevation of a modified form of pin; and

Figure 9 is a cross-sectional view of another modification.

Referring now to the drawing, wherein similar reference characters refer to similar parts throughout the several views thereof, reference character 1 designates a flask here shown to be made of two parts, the reference character 2 designating the cope, and 3 the drag. As shown in Figure 2, the cope is provided with lateral projections 4 and 5, having faces which lie flush with the face 6 of the cope, which is to abut a corresponding face on the drag. These projecting members 4 and 5 are provided with handles 7 and 8 respectively, and in suitable recesses formed partly in the face 6, and in the projecting members, are plates 9 and 10, anchored in position by any suitable means, here shown as screws. The member 9 is shown to have a deep slot 11 cut therein, opening to the outer edge of the projecting member. The member 5 has a bore 12 therethrough, the slot 11 and bore 12 extending upwardly a considerable distance, for a purpose now to be described.

The drag at its upper edge is provided with suitable plates 13 and 14, corresponding to the plates 9 and 10. These plates are provided with apertures through which are inserted the threaded shanks 15 of centering pins, these pins being provided with nuts 16, by which the pins may be anchored to the plates, the nuts lying normally in suitable recesses in the drag.

With reference now to Figure 3, the pin is shown to have a shank 15 as described, and formed integrally with the shank is an enlarged portion 17 overlying the face plate and here shown to be of an arcuate cross-section, but provided with a flat face 18. Anchored by means of a screw 19 which projects into a suitable aperture in the upper end of the enlarged portion 17 is a movable member 20, provided near its lower end with a guide pin 21, which projects into a suitable aperture 22 formed in the member 17. Between the members 17 and 20 there is positioned a slightly arcuate leaf-spring 23, which is anchored on the shank of the screw 19 at its upper end, being also provided with an aperture near its lower end, through which the guide pin 21 projects. Under normal circumstances the spring will hold the member 20

slightly away from the flattened surface of the member 17, as is shown in Figure 3. However, when pressure is placed on the member 20, the spring will collapse and 5 permit the member to lie more closely against the flattened face of member 17.

It will be noted that at their upper ends 10 the members 17 and 20 are slightly beveled so as to be inserted more readily in the bore and slot in the cope. The member 20 is also formed so as to have a flattened surface along its face adjacent the leaf-spring, the rest of the surface of the member 20 being arcuate, so that when the spring 15 is collapsed, the members 20 and 17 will have a nearly circular cross-section.

In the form shown in Figure 3, the member 20, which will hereafter be designated as the "movable" member, extends from one 20 end of the centering pin to the other. In the form shown in Figure 5, which corresponds closely to the form shown in Figure 3, the movable member is anchored in a deep notch cut in one surface of the pin 17. The 25 mounting is exactly similar to the mounting shown in Figure 3, there being provided a leaf-spring and guide pin, as before. In the form shown in Figure 6, the fixed member of the pin has a somewhat square cross- 30 section, and is slotted at its upper end, as indicated at 24. The movable member is also provided with a slot 25, corresponding to slot 24, and mounted in these slots is a tongue 26 anchored to both fixed and 35 movable members by pins 27. On their inner faces, near the lower ends, the fixed and movable members are provided with bored seats 28, in which is mounted a coil spring 29, the spring having a tendency to force 40 the two members apart. The action of this pin is as previously described.

In the form shown in Figure 8, the fixed and movable members are formed integrally, the fixed member terminating in its upper 45 end is a very narrow arcuate portion 30, which in turn increases in size to form a depending portion 31, this corresponding to the movable member in the previous form of pin illustrated.

The portion 31 and member 17 are formed 50 with opposed faces 32 and 33 so that as the member 30 is collapsed against the tension of the arcuate portion 30, the two faces will lie in abutting relation. This type of pin may obviously be made in either square 55 or circular cross-section.

In the form of pin shown in Figure 9, the fixed member 17 forms only about half 60 of the complete pin, the movable member 20 extending from one end of the pin to the other, the two parts being normally spaced free of each other by means of the spring 23, which extends practically the entire length of the pin. The movable member is provided 65 with a guide pin 21, projecting into a bore

22, as previously described in connection with Figure 3, and the movable member is secured to the fixed member by means of a screw 19, which projects into a threaded aperture in the fixed member, the head of the screw lying in a suitable countersunk recess 34. This type of construction has been illustrated in connection with the other types of pins, similar to Figure 9, but not specifically described. 75

In order to use the pins illustrated, one of these pins is mounted on either side of the drag by means of the threaded shank and nut in the apertures provided therefor. The pins extend upwardly and the pin which is to engage in the slot 11, is so fixed in position that its resilient member will lie against one of the side walls of the slot. When the cope is lowered in position, the bore 12 and the slot 11 are caused to pass 80 over the respective pins, and forced downwardly into position against the pressure of the springs. The friction produced will thereby lock the cope and drag together, and by reason of the fixed positions of the pins, the two parts of the flask may be readily centered and the flask locked in assembled relation. When it is desired to remove the cope, the friction of the pins may be overcome by lifting up on the cope 85 by means of the handles, the form of the pins being such as to aid in the release. 90

It will accordingly be seen that I have provided a guide and centering pin, which is well adapted to attain the objects and 100 purposes set forth. The pin may be cheaply constructed, and is composed of a few parts, which are not easily broken. In the event that the surface of the pin becomes worn 105 after use, the shape of the pin itself will compensate for such wear, so that the cope and drag will be perfectly centered and locked in position with sufficient rigidity to serve the desired purpose.

As many changes could be made in this 110 construction without departing from the scope of the following claims, it is intended that all matter contained in the above description or shown in the accompanying drawing shall be interpreted as illustrative 115 only and not in a limiting sense.

Having thus described my invention what I claim as new and desire to secure by Letters Patent is:

1. In a device of the class described, in 120 combination with a flask comprising two or more parts, means to center and hold said parts in definite relation including apertured plates mounted on the contacting faces of one of said parts, and pins on another of 125 said parts adapted to enter said aperture, each of said pins having a rigid member and a resiliently held member normally spaced therefrom.

2. In a device of the class described, in 130

- combination with a flask comprising two or more parts having contact faces, means to center and hold said parts in definite contacting relation, including apertured 5 plates mounted in the contact face of one of said parts, and pins rigidly secured in the face of another of said parts and adapted to engage in said apertures, each of said pins consisting of a fixed member, a member 10 mounted to swing thereon, and resilient means normally holding said last-named member at the extremity of its swing.
3. In a device of the class described, in combination with a flask comprising two or 15 more parts having contact faces, means to center and hold said parts in definite contacting relation, including apertured plates mounted in the contact face of one of said parts, and pins rigidly secured in the 20 face of another of said parts and adapted to engage in said apertures, each of said pins consisting of a rigid part and a movable part adapted to swing relative to said first named part.
- 25 4. In a device of the class described, in combination with a flask comprising two or more parts having contact faces, means to center and hold said parts in definite contacting relation, including apertured plates 30 mounted in the contact face of one of said parts, and pins rigidly secured in the face of another of said parts and adapted to engage in said apertures, each of said pins consisting of a rigid member, a movable 35 member pivotally secured thereto and resilient means to force the free end of said movable member away from said rigid member.
5. In a device of the class described, in 40 combination with a flask comprising two or more parts having contact faces, means to center and hold said parts in definite contacting relation, including apertured plates mounted in the contact face of one of said
- parts, and pins rigidly secured in the face 45 of another of said parts and adapted to engage in said apertures, each of said pins consisting of a rigid member having an arcuate surface and a flat surface, a similarly shaped movable member pivotally 50 mounted on said rigid member so that the flat surfaces are opposed, and a spring positioned between said members to hold said flat surfaces in spaced relation.
6. In a device of the class described, in 55 combination with a flask comprising two or more parts having contact faces, means to center and hold said parts in definite contacting relation, including apertured plates 60 mounted in the contact face of one of said parts, and pins rigidly secured in the face of another of said parts and adapted to engage in said apertures, each of said pins consisting of a rigid member, a movable member, said members having opposed faces, 65 and means normally maintaining said faces in spaced relation.
7. In a device of the class described, in combination with a flask comprising two or 70 more parts having contact faces, means to center and hold said parts in definite contacting relation, including apertured plates 75 mounted in the contact face of one of said parts, and pins rigidly secured in the face of another of said parts and adapted to engage in said apertures, each of said pins 80 consisting of a rigid member provided with an attaching shank, a movable member pivotally mounted near one end of said rigid member, a guide pin on said movable member movable in an aperture in said rigid member, and a leaf-spring mounted between said members and adapted to hold said movable member at the extremity of its pivotal movement.

In testimony whereof I affix my signature.

JOHN A. SPERRY.
